INVENTOR

Clarence D. Platt,

BY

J. S. Nally,

ATTORNEY

UNITED STATES PATENT OFFICE.

CLARENCE D. PLATT, OF BRIDGEPORT, CONNECTICUT.

INCLOSED-SWITCH CONSTRUCTION.

Application filed June 27, 1922. Serial No. 571,289.

To all whom it may concern:

Be it known that I, CLARENCE D. PLATT, a citizen of the United States of America, residing at Bridgeport, Connecticut, have 5 invented a new and useful Inclosed-Switch Construction, of which the following is a specification.

My invention relates to a construction intended to be used with an inclosed switch 10 to facilitate the installation and replacement of fuse plugs without opening the switch box.

The main object is to provide a construction which may be economically produced, 15 and which may be readily attached to or detached from the switch box. Another object is to so construct the attachment that it is durable and not easily broken.

In carrying out the invention I provide an 20 auxiliary fuse receptacle suitably formed of insulating material and provided with shoulders and metallic plates adapted to interlock with the edges of an opening in the side of the switch box or similar receptacle. 25 The fuse receptacle is preferably provided with a hinged cover and catch. The hinges and catch are secured to the body of the fuse receptacle preferably by the same screws which hold the plates in place thus reinforcing the receptacle as well as simplifying the construction of the device.

Fig. 1 is a perspective view of an inclosed switch with fuse plug attachment embodying the improvements of my invention.

Fig. 2 is a perspective view on a larger scale showing the rear of the fuse plug receptacle and a fragment of the switch box detached.

Fig. 3 is a sectional view on the plane of 40 the line 3—3 on Fig. 1 looking upwardly.

Fig. 4 is a perspective view of the fuse plug receptacle detached from the box and with the cover open.

Figs. 5 and 6 are perspective views of the 45 plates or flanges.

Fig. 7 is an end elevation with the cover closed.

The switch box 7 may be of any suitable construction usually having a cover 8 hinged 50 at one end or one side. The circuit wires leading into and out of the box are usually protected in conduits such as 9 and 10. Such a construction also frequently has a meter 11 attached or connected to the box in some

way. When it is desired to prevent access 55 to the switch or the terminals of the circuit within the box it is usual to provide some suitable form of lock or seal to hold the cover closed. Such construction also frequently has interlocking mechanism to prevent operation 60 of the switch handle 12 when the cover is open and to prevent opening of the cover when the switch is closed. As these details are not part of my present invention I refer to them simply as indicating the type of 65 construction to which my invention is particularly adapted without illustrating the same in detail.

In order to make it possible to replace the protective devices such as fuses without 70 opening the cover of the box a special receptacle is provided consisting of an insulating body portion 13 and a cover 14. The body contains sockets such as 15 and 15 adapted to receive ordinary fuse plugs 75 at the front or exposed side. These sockets are connected to binding posts or terminals such as 16, 17, 18 and 19 in the rear of the body adapted to be connected to the proper terminals of the switch within the box and 80 without exposing the wires.

The rear of the body is provided with an extension 20 shaped to enter the slot 21 in one wall of the box. Around this extension is a shoulder or surface 22 adapted to abut 85 the outer surface of the box around the opening 21. The plate flanges 23, 24 and 25 are secured to the rear of the body by means of screws 26, 27, and 28 respectively which pass through the body and are screwed into the 90 plates. The plates are preferably seated on shoulders on the base and are spaced apart from the surface 22 far enough to form grooves adapted to receive the edges of the box around the opening 21. Preferably the 95 tip of the flange 25 is flared outward somewhat so as to facilitate connection with the box. The spring fingers or flanges 23 and 24 may be conveniently formed as integral parts of the plate 29 the outer edge of which 100 is adapted to fit just inside and along the upper edge of the box. By off-setting the ends of the fingers 23 and 24 insertion of the attachment into the slot 21 of the box is facilitated, and these fingers hold the attachment snugly in position in the box without applying undue pressure.

The cover is preferably held in place by

hinges 30 and 31 and a spring catch 32. The hinges are secured to the body by the screws 26 and 27 and to the cover by the screws 33 and 34. By locating these hinges at opposite corners the cover is securely held in register with the base part without straining the material of the body or the cover. The plate 29 which serves as an anchorage for the screws 26 and 27 also reinforces the rear of the body at the place where the greatest strain is applied. The catch 32 may conveniently be held in place by the same screw 28 that anchors the plate 25 to the body.

15 The fingers 23 and 24, and the plate 25 form a three point connection between the body and the box so as to hold the fuse receptacle snugly in place without straining the porcelain even should the wall of the box 20 become bent or distorted.

When the switch box cover is closed, the flange 37 rests along the shoulder 38 of the body 13 and thus holds the body securely in place. To remove the fuse device it is merely necessary to open the cover of the switch box.

Fig. 7 more clearly shows the relation of the plates 25 and 29 to the shoulders on the base. The extension 20 of the base has a recess forming a shoulder 35 on which the plate 25 is seated and a shoulder 36 on which plate 29 is supported. These shoulders are spaced apart from the surface 22 so that, when the plates are in position, there is an open space between the plates and the surface 22 to form grooves for receiving the walls of the box adjacent to the opening 21.

The base is entirely free of overhanging or undercut projections which would be difficult to mold and easily broken in shipment or in use.

Plates 25 and 29 re-inforce the insulating base and form a very practical means for attaching a device of this kind to a switch box. They serve as a means for securing the hinges and catch 32 to the base thus simplifying the construction and they take the place of screws and nuts which would otherwise be required.

50 I claim:

1. In a fuse receptacle, an insulating body, appurtenant fuse terminals mounted on the body, a cover hinged to the body and having a shoulder, a projecting flange on the body 45 for engagement with the edge of an opening in a switch-box, a catch on said body for engagement with said shoulder on the cover, and means for connecting said catch and said flange and securing them on opposite surfaces of the said body.

2. In a fuse receptacle, an insulating body having an extension at the rear adapted to project into an opening in the wall of a switch box, and a plurality of yielding flange 55 members secured to said body at the rear

thereof and projecting laterally therefrom and adapted to co-act with the edges of the wall of a switch box around said opening for securing said receptacle to said box.

3. In a fuse receptacle for an inclosed switch comprising an insulating body, an anchorage plate secured along one edge of the body and having spring fingers for engagement with a switch box.

4. In a construction of the character described 75 a body, a cover, flanges projecting from the rear of said body, hinges between the cover and the body, and screws connecting said hinges to said flanges.

5. In a device of the character described 80 an insulating body, a plate mounted along one edge at the rear thereof and providing a projecting flange, another flange mounted at the opposite edge of the rear of said body and screws connecting said flanges to said 85 body.

6. In a detachable fuse receptacle for an inclosed switch, an insulating base, appurtenant fuse terminals carried by said base, an extension on said base to conform to an 90 opening in one side wall of a switch box and a plate detachably secured upon the said extension having a flange projecting beyond the lateral edge of said extension, the said flange co-acting with one surface of the said 95 base and the side wall of the said extension to form a groove for attaching the said receptacle to a switch box.

7. In a detachable fuse receptacle for an 100 inclosed switch, an insulating base, appurtenant fuse terminals carried by said base, a projecting shoulder integral with said base and a laterally projecting metallic plate on said base adjacent said shoulder, the said shoulder and the said plate co-acting to form 105 a groove for attaching the said receptacle to a switch box.

8. In a fuse receptacle for an inclosed switch, an insulating base having an extension adapted to enter the opening in the 110 wall of a switch box, an abutting shoulder on said base and adjacent to said extension and a plate detachably secured to said base substantially parallel with said shoulder and spaced apart therefrom to form a groove for 115 attachment of the said base to a switch box.

9. In an inclosed switch, a switch box having an opening in one of its walls, a cover for said box, a fuse receptacle having an insulating base, appurtenant fuse terminals 120 carried by said base, a shoulder on said base to conform to an opening in the wall of the switch box and a separately formed plate secured to said base adjacent said shoulder, the said plate and said shoulder co-acting to 125 form a groove for receiving the wall of the box adjacent to the said opening and the box cover being adapted to rest along one side of said base when the cover is closed.

10. In an inclosed switch, a switch box 130

having a U shaped opening in one of its side walls, a cover for the box, an insulating fuse receptacle having appurtenant fuse terminals, an extension on said receptacle to conform to the opening in the box and a metal plate secured upon the extension on the receptacle, the lower surface of the re-

ceptacle, the side walls of said extension and the said plate co-acting to form a groove for attaching the receptacle to the switch box, the cover being adapted to rest along one side of the receptacle when the cover is closed.

CLARENCE D. PLATT.
